(57) **CLAIM**

I claim the ornamental design for a feeding bowl for animals, as shown and described.

DESCRIPTION

FIG. 1 is a top view of a feeding bowl for animals;
 FIG. 2 is bottom view thereof;
 FIG. 3 is a side elevation view of the feeding bowl for animals, the opposite side view being a mirror image thereof;
 FIG. 4 is a rear view thereof;
 FIG. 5 is a top perspective view thereof; and,
 FIG. 6 is a bottom perspective view thereof.
